RAZOR

Edward H. Levitt and Theodore Ulmer, Detroit,
Mich., assignors to Levitt-Ulmer Corporation, a
corporation of Michigan

Application December 11, 1933, Serial No. 701,916

5 Claims. (Cl. 30—12)

This invention relates to razors and more particularly to razors designed for inexpensive manufacture and for sale at a low price, as an advertising or gift novelty.

3 The principal object of the invention is to provide a razor which can be distributed in a book form, simulating the common and well known match-books, in which form matches are now being vended in large quantities, the razor being manipulable to be satisfactory for shaving.

10 Other objects of the invention will presently appear upon reference to the following detailed description of an embodiment thereof, which description can better be understood by reference to the appended drawing. In this drawing,

15 Fig. 1 is a side elevational view of the razor in the form in which it is distributed to the public, namely in a book form, simulating a match book;

20 Fig. 2 is a similar view, but showing the book opened out, and the shank of the razor handle extended;

Fig. 3 is a front view with the parts in the position of Fig. 2;

25 Fig. 4 is a fragmentary side view, to large scale, of the parts, with the head of the razor handle bent back and with the wings of the wrapper bent out, to complete the preparation of the razor for use in shaving;

Fig. 5 is a back view of the razor in the book form in which it is distributed;

30 Fig. 6 is a fragmentary back view of the razor, with the wings of the wrapper bent out to the position of Fig. 4.

Referring to the drawing and more particularly to Fig. 1 thereof, it will be seen that the device of the invention comprises a razor handle, a blade, and a wrapper, all assembled to form a complete article of manufacture.

35 The handle comprises a T-shaped sheet metal part having a head 10 and a shank 11. Disposed against the head 10 is a blade 12 having a sharp edge at 14 spaced away from the serrations 15 at the lower edge of the head 10 by the bead 16 thereon.

40 Embracing the blade and the head 10 is the top edge fold 17 of a sheet of water proof paper or the like, the latter having a front 19 terminating just above the edge 14 of the blade, and also having a back 20, in back of the shank 11. This 45 paper may be of any desired thickness and the terminal line of its back 20 may be at any desired point. Next adjacent the back 20 and terminating at the top edge fold 17 thereof is a back and flap sheet 23 of cardboard or the like upon whose 50 surface 24 may be imprinted advertising matter,

the surface 24 being on the outside of the book when the latter is folded in book form.

A conventional wire staple 25 is passed through aligned holes in the head 10 and the blade 12, the front 19 of the waterproof sheet, and the adjacent portion of the sheet 23 to clamp the parts 10, 12, 19, and 23 into a complete assembly.

50 The shank 11 may be of one long piece, or may be of one short piece provided with an extension arranged to telescope on the shank. The latter construction is shown, and as can be seen, the lower end of the shank 11 is bent over at its corners to provide wings 30 which receive between them the tapered end 31 of a shank extension 32, the latter being slideable along the shank 11. The extension 32 can be withdrawn from the shank 11 to a limited degree, without the possibility of its being completely separated therefrom, and when withdrawn locks in place due to the taper lock 30—31. The lower end of 55 the extension 32 is provided with a hump 33 and a tongue 34 which may be passed through aligned slits 35 in the flap or lower part of sheet 23 to anchor the flap to the shank 11, through the medium of the friction taper-lock 30—31, when the 60 parts are opened out for use as a razor.

65 The sheet 23 further is provided with slits 36 for purposes later to be described and these are disposed as shown, adjacent the upper end of the shank 11, near the intersection thereof with the 70 head 11.

75 The operation and use of the device shown will now be described. The device is distributed to the public in book form, substantially as shown in Fig. 1, with all of the metal parts concealed within the wrapper; the free edge 37 of the flap of sheet 23 is tucked into the top edge fold 17, i. e., into the space between the blade 12 and the front 19 of the waterproof sheet, substantially as indicated. At this time the extension 32 is telescoped onto the shank 11 so that the combined length of the shank 11 and its extension is somewhat less than the length of the folded book. As thus formed to be distributed, the book forms a very satisfactory advertising novelty and 80 presents no metal parts which might be considered objectionable. Further, inasmuch as the surface 24 of the flap sheet 23 may be imprinted throughout its area with advertising matter, practically all the available area of the book is 85 used for advertising and there are no blank areas on the exterior of the book.

90 When the device is to be used as a razor, the book is first opened up, with the sheet 23 assuming the position of Figs. 2 and 3. At this time, the 95 100 105 110

extension 32, which had remained telescoped onto the shank 11, is pulled out to its full extent. Simultaneously, the tongue 34 of the extension 32 is passed through the slits 35 of the flap of sheet 5 23 so as to anchor the flap of sheet 23 to the razor handle.

Then the head 10 is bent back, relative to the shank 11, or substantially to the position of Fig. 4, which act serves to move all the parts stapled 10 to the head, (blade 12, front 19, and sheet 23) back to the position of Fig. 4, thus forming a satisfactory razor. The degree of bending may be left to the discretion of the user, and it will be observed that any shaving angle may be created, 15 this feature being of advantage inasmuch as certain people prefer one shaving angle and other people prefer a different shaving angle.

The last step in preparing the device for use as a razor, is to bend the flap sheet 23 from the form 20 of Fig. 5 to the form of Fig. 6, so as to provide two wings 38, between which is a channel 39. It is observed that the extension 32 is anchored to the base of this channel by virtue of the fact that the slits 35 extend across the base of the 25 channel.

For shaving, the operator grasps the razor as follows: He places his index finger in the channel 30 39 between the wings 38 and then grasps the wings 38 with his thumb against the outside of one of them and his middle finger against the outside of the other, these three digits together being all that are necessary to grasp the razor satisfactorily.

If the handle shank is formed of one part, the 35 handle shank will be made as long as the shank 11 and the extension 32, and will be bent or re-troverted when the device is in book form, and will be straightened out when the book is opened up, to form a long handle shank.

40 Further, while the wrapper is shown as composed of two separate sheets of paper, it will readily be understood that they might well be made integral.

Further, while the head 10 and shank 11 are 45 shown as integral, they might well be separate, to be joined at their intersection by a rivet or the like.

Now having described an embodiment of the 50 invention, reference will be had to the following claims for a determination of the scope of the invention.

We claim as our invention:

1. A device of the character described com-

55

70

75

prising a wrapper of paper or the like folded in the form of a match book outer wrapper to provide a front, a top-edge fold, a back, a bottom edge fold, and a flap whose free edge may be tucked into the top edge fold, a razor blade in the top edge fold, and a razor handle having its head in the top edge fold and its shank in the space between the flap and the back. 80

2. A device of the character described comprising a wrapper of paper or the like folded in the form of a match book outer wrapper to provide a front, a top-edge fold, a back, a bottom edge fold, and a flap whose free edge may be tucked into the top edge fold, a razor blade in the top edge fold, and a T-shaped razor handle having its head in the top edge fold and its shank in the space between the flap and the back. 85

3. A device of the character described comprising a wrapper of paper or the like folded in the form of a match book outer wrapper to provide a front, a top-edge fold, a back, a bottom edge fold, and a flap whose free edge may be tucked into the top edge fold, a razor blade in the top edge fold, and a razor handle having its head in the top edge fold and its shank in the space between the flap and the back, the shank being telescopically constructed. 90

4. A device of the character described comprising a wrapper of paper or the like folded in the form of a match book outer wrapper to provide a front, a top-edge fold, a back, a bottom edge fold, and a flap whose free edge may be tucked into the top edge fold, a razor blade in the top edge fold, and a razor handle having its head in the top edge fold and its shank in the space between the flap and the back, the shank being telescopically constructed, the front, the blade, the head, and the back being integrally joined. 105

5. A device of the character described comprising a wrapper of paper or the like folded in the form of a match book outer wrapper to provide a front, a top-edge fold, a back, a bottom edge fold, and a flap whose free edge may be tucked into the top edge fold, a razor blade in the top edge fold, and a razor handle having its head in the top edge fold and its shank in the space between the flap and the back, the shank being telescopically constructed, the front, the blade, the head, and the back being integrally joined, 120 by means passing through them. 125
